(57) CLAIM

We claim the ornamental design for a robotic cleaner, as shown and described.

DESCRIPTION

FIG. 1 is a front perspective view of a robotic cleaner, showing our new design;

FIG. 2 is a top view thereof;

FIG. 3 is a bottom view thereof;

FIG. 4 is a front view thereof;

FIG. 5 is a right-side view thereof;

FIG. 6 is a rear view thereof; and,

FIG. 7 is a left side view thereof.

The broken lines shown in the drawings illustrate portions of the robotic cleaner that form no part of claimed design.
